COMBINED BRUSH AND COMB

Joseph Vallis, Toronto, Ontario, Canada, assignor to Valden Company, Toronto, Ontario, Canada

Filed Aug. 10, 1965, Ser. No. 86,525

Term of patent 14 years

(Cl. D9—2)

FIG. 1 is a top view of a combined brush and comb, showing my new design;

FIG. 2 is a side view thereof; and

FIG. 3 is a bottom view thereof.

I claim:

The ornamental design for a combined brush and comb, as shown.
